UNITED STATES PATENT OFFICE.

WALTER W. IHNE, OF CHICAGO, ILLINOIS.

ERASER FOR FOUNTAIN-PEN CAPS.

1,215,538.

Specification of Letters Patent. Patented Feb. 13, 1917.

Application filed October 23, 1916. Serial No. 127,210.

To all whom it may concern:

Be it known that I, WALTER W. IHNE, a citizen of the United States, residing at Chicago, in the county of Cook and State of Illinois, have invented certain new and useful Improvements in Erasers for Fountain-Pen Caps, of which the following is a specification, reference being had therein to the accompanying drawing.

10 This invention relates to improvements in erasers for fountain pen caps, one object of the invention being the provision of a novel form of pen cap in which the closed end is sealed by a removable eraser carrying member which is readily concealed when not in use and is easily accessible when it is desired to use the same.

15 A further object of this invention is the provision of an eraser attachment for pen caps in which the eraser element when composed of a rubber composition or the like may be readily renewed and which may be interchanged when desired with a knife or cutting eraser.

20 In the accompanying drawings:

Figure 1 is a side elevation, partly in section, of a fountain pen cap provided with the present invention.

25 Fig. 2 is a side elevation of the eraser carrying member *per se*.

Fig. 3 is a view in elevation of the knife eraser *per se*.

Fig. 4 is a modified form of the knife eraser.

30 Referring to the drawings and more particularly to Figs. 1 and 2 thereof, the numeral 1 designates the eraser member which is here composed of a rubber composition, the same being provided with a head 5 which

35 is adapted to fit within the socket of the member 3 after the stem of the eraser has been projected through the tubular member 2. The tubular member 2 threadedly engages the member 3 so as to clamp the

40 head 5 firmly in place, the mill head of the member 2 being adapted to engage the inner end of the reduced exteriorly threaded portion of the member 3 so that the parts when

45 in the cap 4 will assume the position as shown in Fig. 1, the eraser being concealed or when the eraser is in use, being detached as shown in Fig. 2.

50 Where so desired, the member 1' may be

substituted for the member 1, the same being provided with a knife blade 6 while the shank of the member 1' is made of metal and preferably integral with the blade. As shown in Fig. 4 the member 3' is attached directly to the knife eraser 1'', thus dispensing with the locking member 2.

55 From the foregoing description it is evident that the parts 2 and 3 may be constructed of the same material as the cap 4 or any desired material that will accomplish the purpose.

60 What I claim as new is:

1. The combination with a fountain pen cap, of a removable eraser member attached to one end thereof and when not in use forming a closure for the cap, the latter including an exteriorly threaded tubular member, an erasing member mounted therein and provided with a disk head upon one end and a concealing member for the cap having an interiorly threaded socket for receiving the tubular member and co-operating therewith to clamp the erasing member firmly in place.

65 2. The combination with a fountain pen cap, of a removable eraser member attached to one end thereof and when not in use forming a closure for the cap, the latter including a closure for the reduced portion for engaging the cap and being further provided with an interior screw threaded socket, an erasing member having a cylindrical shank and a disk head, the head of which seats within the socket adjacent the closed end thereof, and a tubular locking member receiving the shank of the erasing member and fitting within the socket of the closure to clamp the erasing member in position.

70 3. A fountain pen cap open at both ends one end of the cap being interiorly screw-threaded, a closing plug for the cap having an internally threaded socket and an exteriorly threaded reduced portion, the latter portion being adapted to engage the threads of the cap to close the end of the cap, an erasing member having a shank terminated in a flat head upon one end, said head being adapted to fit within the socket of the closure member against the bottom thereof, and an eraser locking member consisting of a tubular double diameter member the reduced diameter being exteriorly threaded

and being adapted to threadedly engage the
socket of the closure member, the shank of
the eraser being mounted through said tu-
bular member and having its disk head
5 clamped firmly against the bottom of the
socket of the closure member.

In testimony whereof I affix my signature
in presence of two witnesses.

WALTER W. IHNE.
